UNITED STATES PATENT OFFICE.

GEORGE C. SUTTON, ISAAC W. CROWL, AND JOHN O. HAMBERG, OF PRIEST RIVER,
IDAHO.

APPARATUS FOR BURNING STUMPS.

1,111,241.

Specification of Letters Patent. Patented Sept. 22, 1914.

Application filed April 15, 1913. Serial No. 761,231.

To all whom it may concern:

Be it known that we, GEORGE C. SUTTON, ISAAC W. CROWL, and JOHN O. HAMBERG, citizens of the United States, residing at 5 Priest River, county of Bonner, and State of Idaho, have invented certain new and useful Improvements in Apparatus for Burning Stumps, of which the following is a specification.

10 This invention relates to apparatus for burning stumps.

Our object is to provide an improved apparatus for burning stumps whereby combustion may be initiated and continued in 15 the interior of the stump, draft prevented through the cut-off or exposed top of the stump, and the products of combustion conveyed from the interior of the stump for extraction or recovery, by distillation or condensation, of the commercially valuable 20 products such as tar, acids, etc., contained in the stump and the valueless products passed off into the atmosphere.

The invention consists of draft and take-off 25 apparatus combined with a cap which is used to seal the exposed upper face or top of the stump, as fully set forth hereinafter.

The accompanying drawing is a perspective, with certain parts broken away, showing 30 the apparatus.

Preferably, at or near the center of the stump 1 a hole 2 is bored down from the upper face thereof, a suitable distance, say ten or twelve inches below the level of the 35 earth outside the stump. Another hole 3 is then bored into the stump in a general lateral direction, commencing about the level of the earth and inclined downwardly so that it will intersect the hole 2 at or near the 40 lower end thereof. A fire is then started, by any suitable means or in any preferred manner at or about the point 2^a where the holes 2 and 3 intersect and the combustion is allowed to continue until the upper end 45 part of the hole 2 has become slightly enlarged. A pipe 4, preferably of metal, and provided with any suitable air valve or controlling device 5 at its outer part, is inserted in the hole 3 to within a few inches of where 50 holes 2 and 3 intersect at 2^a. This pipe constitutes a draft pipe and the amount of air admitted to the fire at 2^a may be regulated by the valve 5.

At or about the time the pipe 4 is inserted, 55 a pipe 6, preferably of metal, and of suitable

diameter, say two inches, more or less, is inserted in the hole 2 after the said hole 2 has become slightly enlarged at its top by the fire. The pipe 6 is entered into the hole 2 to a distance within a few inches above 60 the point 2^a, the upper end of the pipe extending above the top of the stump. A flat sheet of metal 7 is then fastened to the top of the stump by nails or other fastenings 7^a, or otherwise positioned thereon and it is provided with any suitable means such as 7^b to engage the pipe 6 and prevent the latter from dropping. The plate or disk 7 prevents the fire from breaking out around the point where the pipe 6 passes through the 70 upper face of the stump and also keeps the stump from burning to any appreciable extent above the lower end of the pipe 6 by preventing draft through the previously exposed upper face of the stump. 75

The foregoing steps having been taken, a hood or cover 8 of any desired form and preferably of metal, is placed around the stump and incloses it and the pipe 6 and plate 7, this hood 8 being preferably considerably larger than the stump to allow a free space between it and the stump. The hood is provided with a damper or valve 9 for the admission of any desired amount of air to mix with the products of combustion 80 coming out of the pipe 6 for the purpose of cooling such products of combustion and to render their subsequent condensation more 85 rapid.

An elbow 10 connects the open upper end 90 of the hood 8 to a generally laterally disposed pipe 11, said pipe and elbow 10 being preferably several inches in diameter. The pipe 11 takes off the products of combustion from which the commercially valuable 95 products such as tar, acids, etc. may be recovered by condensation, distillation, or in any other suitable manner.

As soon as the fire has gotten well under way in the center of the stump 1, the draft 100 through the pipes 4 and 11 is partially cut off by regulating damper 5. The stump then acts as a retort and the smoke and gases generated by the combustion within, pass up through hood 8, and pipe 11. In this manner the stump 1 is entirely consumed eventually and the valuable distillates therefrom are obtained. 105

The apparatus may be made in several sizes adapting it to stumps of different sizes. 110

Having thus described our invention, what we claim as new and desire to secure by Letters Patent, is:—

1. An apparatus for burning stumps, embodying a pipe extending within the stump and adapted for conveying off the products of combustion from the interior of the stump, and a cap combined with said pipe which is located directly on top of and covering the stump.
2. An apparatus for burning stumps, embodying a pipe extending within the stump and adapted for conveying off the products

of combustion from the interior of the stump, a cap combined with said pipe which is located directly on top of and covering the stump, and a draft supplying pipe inserted laterally in the stump.

In testimony whereof, we hereunto affix our signatures in presence of two witnesses.

GEORGE C. SUTTON.

ISAAC W. CROWL.

JOHN O. HAMBERG.
